CABINET DRAWER

Filed Dec. 17, 1921

Inventor:
John B. O'Connor
By Cheever, Cox & Atty

Patented Dec. 11, 1923.

UNITED STATES PATENT OFFICE.

JOHN B. O'CONNOR, OF AURORA, ILLINOIS, ASSIGNOR TO LYON METALLIC MANUFACTURING COMPANY, OF AURORA, ILLINOIS, A CORPORATION OF ILLINOIS.

CABINET DRAWER.

Application filed December 17, 1921. Serial No. 522,994.

To all whom it may concern:

Be it known that I, JOHN B. O'CONNOR, a citizen of the United States, residing at Aurora, in the county of Kane and State of Illinois, have invented a certain new and useful Improvement in Cabinet Drawers, of which the following is a specification.

My invention relates to drawers for cabinets and the like, and one of the objects of 10 the invention is to provide a simple and convenient retainer for holding down the forward edges of blueprints, drawings or other objects that may be contained within the drawer. Among other uses it may be mentioned that it is common practice in drafting rooms and elsewhere to keep blueprints and drawings in shallow drawers mounted in cabinets made for the purpose. It frequently happens in such cases that the forward edges of the sheets curl up and jamb 20 when the drawer is being opened. One of my objects is to provide a retainer which will prevent this and hold the sheets in such shape that the drawer may be readily closed 25 or opened and the drawings held neatly and securely in place. Drawings, blue prints and the like are, of course, of various sizes and dividers are frequently used for subdividing the drawers. The object of my 30 invention is to provide a retainer so constructed as to permit of the use of such dividers.

I attain my objects by the mechanism illustrated in the accompanying figures in 35 which

Figure 1 is a perspective assembly view showing a drawer embodying my improvements in position in a cabinet.

Figure 2 is a vertical section of parts 40 shown in Figure 1, the plane of section extending in a direction from front to rear of the cabinet.

Figure 3 is a perspective view of the label holder showing the same in attached position.

Figure 4 is a sectional detail taken on the line 4—4, Figure 2.

Figure 5 is a fragmentary perspective view of a divider.

Like numerals denote like parts throughout the several views.

In the form illustrated, the cabinet 1 has horizontal guides 2 for supporting and guiding the drawers 3. Dividers 4 may be 55 fastened within the drawers at various

points as needs may require. For this purpose the bottom of the drawer is space-punched, as illustrated. In the form shown, see especially Figure 5, each divider has a base 5 which may be bolted to the bottom 60 of the drawer, and a tongue 7 adapted to project thru suitable slots in the drawer front. The design of these parts may be considerably varied without departing from the spirit of the invention.

Hinged to the front of the drawer is a guard or retainer 6 adapted when in acting position to overlie the front end of blue prints, tracings, drawings and like articles 70 to hold them down and prevent any possibility of their curling up or becoming jammed when the drawer is operated. The retainer is notched or otherwise so formed as to avoid interference with the dividers 75 no matter where the latter are placed.

In the drawings I have shown a particularly simple and advantageous form of retainer which consists of a single piece of wire having a series of reverse bends of such number and shape that the retainer as 80 a whole resembles a strip arranged lengthwise of the drawer and of a few inches in width. In the present case these reverse bends have parallel sides so that the retainer 85 may be said to consist of a plurality of U-shaped bends arranged alternately, some of the bends being open towards the back and others towards the front. The retainer is hinged to the front of the drawer by means of eyelets 8 or other appropriate devices. Thus the retainer may be swung down to acting position shown in Figures 1 and 2 or may be swung up to vertical position for non-interference with the contents 90 of the drawer when the latter are being removed. When swung down, the retainer will straddle the dividers, regardless of their number or the positions to which they are adjusted.

Referring now to the label holders, these 100 are designed especially for the type of retainer illustrated. They consist of a rectangular piece of sheet metal having end flanges or lips 11 as best shown in Figure 3. The purpose of these end flanges is to hold 105 a card or label in place. By preference side flanges 12 are also provided for preventing lateral movement of the label. The label holders are held in place by integral clips 14 which snap over two adjacent arms of the 110

retainer. Being of sheet metal, the clips are resilient and the label holder may be readily applied by merely pressing the clips over the arms of the retainer, and may be 5 removed by exerting slight pressure to force them off.

Now referring to the stop which prevents the drawer from being pulled too far out of the cabinet:

- 10 The guides 2 previously mentioned are formed of sheet metal and have upstruck lugs 16 projecting inward, as best shown in Figures 2 and 4. An arm 18 is pivoted to each side of the drawer upon pins 19 in 15 such manner as to swing in a vertical plane. The bottom of the drawer has slots 20 through which the lower end of the arm may project. By preference these slots are not located immediately adjacent to the sides 20 of the drawer, but at a slight distance therefrom, as best shown in Figure 1. A shoulder 21 is formed in the arms, which shoulder is adapted to strike the bottom of the drawer and limit the downward and backward 25 movement of the arm. The result is that when the arm is down in acting position, it cannot be swung any further backward, but can be readily swung forward and upward to dotted line position shown in Figure 2. 30 When the arm is down in acting position shown in full lines in the drawing, the lower projecting end will engage the stops 16 in time to prevent the drawer from being pulled too far out. If it is desired to actually 35 remove the drawer from the cabinet, all that is necessary is for the operator to reach into the drawer, swing the arm 18 from acting position shown in full lines, Figure 2, to non-acting position, shown in 40 dotted lines, Figure 2, after which the drawer may be taken out.

It will be evident that the device herein-

above described renders the cabinet convenient and efficient at a very small cost above that which would be entailed if these improvements would be omitted.

As to the stop arm 18, it would operate to a certain degree if its downward movement were limited simply by engagement with the rear end of the slot 20; but constant shock due to successive and vigorous pulls on the drawer would tend to tear or disrupt the metal of which the bottom of the drawer is formed. According to the preferred form of the invention illustrated 55 in the drawings, the shoulder 21 of the arm contacts a considerable area of the bottom of the drawer and thus distributes the strain and prevents any appreciable degree of wear.

Having thus described my invention, what 60 I claim as new and desire to secure by Letters Patent is:

1. The combination with a drawer for cabinets and the like of a retainer hinged to the front of the drawer so as to swing 65 about a horizontal axis and to permit the free edge to be lowered on to the drawer contents, said retainer having slots for accommodating dividers mounted in the drawer.

2. In a cabinet, the combination with the main framework of a drawer slidingly mounted therein, a retainer consisting of a wire having a series of reverse bends adapted to form slots for accommodating dividers, 75 said bends lying in a common plane and having the general form of an elongated rectangle, portions of the wire running parallel to the drawer front, and means adapted to pivotally connect said portions to the drawer 80 front.

In witness whereof, I have hereunto subscribed my name.

JOHN B. O'CONNOR.
